UNITED STATES PATENT OFFICE.

ANDREW J. JOHNSTON, OF LIVERPOOL, ENGLAND.

ENVELOP AND BLANK THEREFOR.

SPECIFICATION forming part of Letters Patent No. 699,875, dated May 13, 1902.

Application filed November 23, 1900. Serial No. 37,520. (No model.)

To all whom it may concern:

Be it known that I, ANDREW JAMES JOHNSTON, a subject of the Queen of Great Britain, residing at Liverpool, in the county of Lancaster, England, have invented certain new and useful Improvements in Envelops and Blanks Therefor, of which the following is a specification.

Type-writing on envelopes for correspondence purposes, labels, and the like is more or less difficult and tedious work, owing to it being necessary to feed each separately into the machine. My present invention is designed to avoid these defects.

Figures 1 and 2 show my invention as applied to an envelop.

In this case the envelop is made from a blank, such as that shown in Fig. 2, formed with flaps D and perforated at E in parallel lines at intervals, and also provided with fillets of gum or other adhesive substance at the perforations E and at the ends F, as shown by the shade-lines. The blank is then folded at right angles to the perforations along the line G, the adhesive fillets causing the folded blank to adhere along the lines of fillets, and thus form a series of envelopes all connected together, as shown in Fig. 1. They can be typed on in the machine while in the strip and then afterward separated by tearing them along the perforated lines. Separate envelopes are thus obtained of the usual shape.

It will readily be seen by reference to the drawings that the blank has flaps D arranged in a series upon one edge thereof, each corresponding to its respective envelop, and the opposite edge of the blank is formed with a series of cut-away portions corresponding in number and in line with the flaps. The strips of gum extending transversely of said blank are preferably arranged to extend from points on the edge of the blank midway between the flaps to points midway between said cut-away portions, the said gum strips being of a uniform width, whereby when the lower portion of the blank is folded upon the upper and secured directly thereto by said gum envelopes of uniform rectangular shape will be produced.

I claim as my invention—

1. An improved article of manufacture, consisting of a blank provided with a series of tabs at one edge, and a series of cut-away por-

tions approximately semicircular in shape in the other edge in the same relative plane as the tab portions, strips of gum or other adhesive substance extending transversely of said blank from points between said tabs on one edge to points in the same relative plane between the said cut-away portions of the opposite edge, said gum strips being of uniform width throughout their length, the lower portion of said blank being designed to be folded upon and directly secured to the remainder thereof, by means of said gum strips, for forming a series of envelopes each having a rectangular inclosing space, the said blank having a single line of perforations extending through the central longitudinal line of each of said strips of gum, whereby the envelopes may easily be torn apart without interfering with the adhesion of the gum strips, thereby facilitating the passage of the envelopes through a type-writer in sheet or strip form before separation, substantially as described.

2. An improved article of manufacture, consisting of a single blank having one edge provided with a series of flaps or extensions, and the opposite edge provided with a series of cut-away portions, corresponding in number and in line with the said flaps, a strip of gum or other adhesive material extending from a point midway between each flap to a point midway between each cut-away portion of uniform width throughout its length, a single line of perforations extending along through the central line of each of said gummed portions, the construction and arrangement being such that when one portion of the blank is folded upon the other, and caused to adhere directly thereto substantially as described, a series of envelopes is formed having rectangular inclosing spaces, each envelop of the series being easily capable of separation by tearing along the line of perforations, whereby the passage of the envelopes through a type-writer in sheet or strip form is facilitated.

In witness whereof I have hereunto signed my name, this 14th day of November, 1900, in the presence of two subscribing witnesses.

A. J. JOHNSTON.
